UNITED STATES PATENT OFFICE

2,122,340

SERVICE COCK KEY AND CURB BOX
CLEANER

George W. Durno, Pittsburgh, Pa.

Application March 2, 1936, Serial No. 66,729
Renewed September 9, 1937

1 Claim. (Cl. 294—100)

The invention relates to a duplex tool and more especially to a combination service cock key and curb box cleaner.

The primary object of the invention is the provision of a tool of this character, wherein a curb cock or valve within a curb box can be readily and easily operated irrespective of the accumulation of dirt, trash or foreign matter as may be present within the box and often found there-
10 in constituting a barrier for access to the valve or cock as such dirt or foreign matter can be conveniently and easily removed for the successful working of the valve, the tool being novel in construction and is readily and easily handled
15 for service as a key or a cleaner.

Another object of the invention is the provision of a tool of this character, wherein a sleeve is employed and in the latter is slidably mounted a rod to which is detachably coupled a gripping tool having spring arms, these cooperating with each other for removal of foreign matter or the like from curb boxes and such rod is provided with a terminal wrench serving as a key for operating a valve within the curb box, the rod 25 being readily movable through the sleeve for the contracting of the spring arms of the grappling tool for the successful removal of dirt from the curb box.

A further object of the invention is the provision of a tool of this character, which is simple in construction, readily and easily carried from place to place, thoroughly reliable and efficient in its operation, strong, durable, and inexpensive to manufacture.

35 With these and other objects in view, the invention consists in the features of construction, combination and arrangement of parts as will be hereinafter more fully described, illustrated in the accompanying drawing, which discloses the 40 preferred embodiment of the invention and pointed out in the claims hereunto appended.

In the accompanying drawing:

Figure 1 is a vertical longitudinal sectional view through a tool constructed in accordance 45 with the invention and shown partly broken away.

Figure 2 is an elevation of the gripping or grapple end of the tool.

Figure 3 is an elevation of the tool and shown 50 gripping foreign matter.

Similar reference characters indicate corresponding parts throughout the several views in the drawing.

Referring to the drawing in detail, the tool 55 comprises a tubular barrel 10 which is of tapered formation and of the required length while in-

teriorly of the smaller end of said barrel is a reinforcing collar 11, if being fixed in any desirable manner while the opposite larger end 12 constitutes a flare. Slidably fitted within the barrel 10 is a rod 13 and threaded in the smaller end and its companion collar 11 is a binding screw 14 which engages the rod 13 to hold the same adjusted and this screw is formed with a winged head 15. The rod 13 at its outermost end has formed therewith a wrench head 16 10 providing a key for a service cock or valve within a curb box (not shown).

The inner end of the rod 13 carries a threaded coupling collar 17 for detachably fastening to the rod the stem 18 of a gripper or grapple having the outwardly arched spring fingers or arms 19, these being approximately flattened with dished inner surfaces 20 to provide cavities therein while near the outer free ends of the fingers or arms are inwardly directed teeth or spurs 21 so that such fingers or arms will grab a quantity of dirt, trash or foreign matter when the said fingers or arms are active against the flared end 12 of the tube 10 when the rod 13 is drawn upwardly therethrough.

The flared end 12 of the tube 10 acts upon the outwardly arched fingers or arms 19 to move the same together on the drawing inwardly of the rod 13 in the working of the tool for the grasping of dirt, trash or foreign matter from within a curb box (not shown).

The tool is hand operated either for service as a wrench or key and for extracting or removal of dirt, trash or foreign matter from within a curb box.

What is claimed is:

A tool of the character described comprising a tapered tubular body open at opposite ends, a collar fitting the smaller end of said body and having a flat faced opening, a rod slidable in said body and fitting the opening in said collar for holding said rod against rotation, a coupling sleeve on the inner end of said rod, a stem detachably threaded in the coupling sleeve, opposed outwardly divergent spring arms fixed to 45 said stem, the arms being bent intermediate thereof to have the outer ends of said arms straight and parallel with each other, spurs bent from and extended inwardly of the spring arms at their outer free ends, and means threaded in the smaller end of the body and said collar for locking the rod against sliding movement therein, the spring arms being adapted to work through the larger end of the body for expansion and contraction of said arms.

GEORGE W. DURNO.
